UNITED STATES PATENT OFFICE.

EDWIN H. HANEY, OF LOS ANGELES, CALIFORNIA.

LUBRICATING SYSTEM FOR AUTOMOBILES.

Application filed November 28, 1921. Serial No. 313,863.

To all whom it may concern:

Be it known that I, EDWIN H. HANEY, a citizen of the United States, residing at Los Angeles, county of Los Angeles, State of California, have invented certain new and useful Improvements in Lubricating Systems for Automobiles; and I do declare the following to be a full, clear, and exact description of the same, reference being had to the accompanying drawings, and to the characters of reference marked thereon, which form a part of this application.

This invention relates to improvements in lubricating systems for automotive vehicles of all kinds, the principal object of my invention being to provide a system having its main oil tank located at such a point that it may be easily and quickly filled without the danger of spilling and wasting the oil on the outer surface of the engine as now frequently occurs owing to the usually awkward and inconvenient location of the filler-hole of the crank case, where the main supply is usually carried.

I have also arranged for a reserve supply of oil being carried, sufficient to run a car for some hundreds of miles, the oil from which reserve may be fed into the crank case when necessary without the driver leaving his seat or stopping the car to do so.

I have also provided leads from this reserve supply tank to all joints or bearings of the car which occasionally need lubricating with oil, besides the main crank shaft and engine bearings, the feed to which leads is also controllable at will by the driver of the car from his seat.

My system therefore has four distinct points of advantage over the usual systems, greater cleanliness and ease in filling, a reserve or emergency supply of oil, a means for oiling all necessary parts of the car from a common point, and a centralized and easily operated individual control means for the leads to all the parts.

I thus do away with the necessity (frequently overlooked on account of the inconvenience involved) of the driver having to pass around or under his car to oil various individual and widely separated members.

I also do away with the filling of the oil into the crank case as is now done, at a point relatively low on the engine where dirt and dust, caked with oil and grease, is bound to accumulate, some of which can hardly be prevented from being passed into

the oil filling hole along with the fresh oil, to the ultimate detriment of the engine owing to the abrasive action of the foreign matter thus mixed with the oil.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claim.

In the drawings similar characters of reference indicate corresponding parts in the several views.

Fig. 1 is a side outline of the front end of a motor-car chassis, showing my improved system installed thereon.

Fig. 2 is an enlarged detached section of the oil tank.

Fig. 3 is a front view of an oil feed control or dial board.

Referring now more particularly to the characters of reference on the drawings, Fig. 20 numeral 1 denotes in general the engine of a car, having the usual crank case 2 and oil-filling tube 3 therefor. The wheel supporting main-springs 4 are mounted as usual to the frame 5 of the car by shackles 6 or other form of connection.

My improved lubricating system comprises a tank 7, preferably mounted under the hood and on top of the engine, being supported from the latter by feet 8 and clamped in position by straps 9.

This tank is of a size to hold a predetermined amount of oil, preferably about a gallon, and is divided into two compartments by a partition 10, each compartment having a filler hole and cap 11 on top, which will be evident is well above the line of any dirt and dust, which is prevented from accumulating by the draft created by the usual cooling fan.

Glass gages 12 on the sides of the tank denote at a glance the amount of oil in the respective compartments.

A pipe 13 leads into the tube 3 and has a rubber gasket 14 thereabout and seated over said tube to exclude all dirt and dust.

From the pipe 13 branch pipes 15 lead to the tank compartments, each such branch pipe having a valve 16 controlled by a handled stem 17 leading to a control or dial board 18 mounted on the dash board of the car.

From either compartment of the tank a pipe 19 leads to the packing gland of the water circulating pump 20, the feed through this pipe being controlled by a valve operated by means of a stem 21 projecting through the board 18.

Other pipes 22, suitably branched, lead to the front and rear spring shackles and joints, and are provided with valves each 19 individually controlled by handled stems 23 passing through the control board 18, which is suitably lettered so that the driver will know which one to manipulate when he desires to feed oil to any certain part.

15 Additional pipes may be led to other members of the car if desired, but those shown are sufficient to illustrate the possibilities of the system.

Since the pipes 19, 22 etc. are quite small 20 and apt to have a good many curves in their extent, there is considerable surface friction tending to retard the passage of the oil, which would flow very sluggishly.

I therefore preferably provide means for 25 maintaining the oil in the tank under pressure, such as a hand pump 24 whose handle 25 is positioned adjacent the valve control members on the board 18, thus providing a compact and centralized control member for 30 the entire system.

In operation, when filling the tank and crank case at the outset, either of the valves 16 is left open while oil is poured into the tank until the crank case is filled to its normal level as indicated by the usual gage 35 provided thereon.

The valve 16 may then be closed, and enough oil fed into the tank to fill both compartments, thus giving a reserve supply which can be fed to the crank case or other 40 points whenever necessary.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the 50 spirit of the invention, as defined by the appended claim.

Having thus described my invention, what I claim as new and useful and desire to secure by Letters Patent, is:—

The combination with a motor vehicle lubricating system comprising a reservoir and a series of conduits separately connected with the reservoir and to various points of the vehicle, each conduit having a separate 60 control valve, of a control board located adjacent the dash board of the vehicle and having a series of designations thereon corresponding to the points of the vehicle to which the conduits lead, and a valve stem 65 on each valve leading through the control board adjacent the proper designation for the control of the lubricant through its corresponding conduit.

In testimony whereof I affix my signature.

EDWIN H. HANEY.
